BURIAL CASKET

Rudolph B. Beranek, Detroit, Mich.

Application July 20, 1940, Serial No. 346,637

4 Claims. (Cl. 27—35)

This invention relates to burial caskets of that type wherein a decorative outer casket or casing houses and conceals an inner, relatively inexpensive interment casket preparatory to and during the burial service.

Caskets of this type have a relatively large field of use among persons of limited means, since they lend comfort and solace to the mourners by avoiding the appearance of cheapness and drabness, while at the same time materially reducing the cost of the service. Heretofore, however, casket construction of this type has embodied certain objectionable features, among which may be mentioned a relatively loose and sometimes rickety fit between the outer and inner caskets, the exposure of a part or parts of the inner casket when the outer casket is opened, and the complexity of the operating mechanism for releasing the inner casket during interment.

The present invention, therefore, includes among its objects to provide a casket which, while being in reality of the double type, provides such a snug fit between the outer and inner shells or caskets as to simulate a practically single unit; to provide a casket of the type specified wherein the interment box is fully concealed when the outer or main casket is opened, and to provide releasing mechanism for the inner casket or interment box which is relatively simple in construction and operation.

The foregoing and other objects and advantages will become apparent in view of the following description taken in conjunction with the drawing, wherein:

Fig. 1 is a view in side elevation of a casket constructed in accordance with the features of the present invention with the lid in open position;

Fig. 2 is a section taken substantially on the line 2—2, Fig. 1;

Fig. 3 is a view in section similar to Fig. 2 except that the lid is shown in closed position; and

Fig. 4 is a plan view of the casket with one end partially broken away to show the release mechanism for the inner casket.

Referring to the drawing in detail, the main outer casket is generally indicated at 10 and may be of ornate design and of permanent relatively expensive construction, the particular design forming no part of the invention. The outer casket has hinged covers or lids 11, 11a and 11b, side walls 12, 12a and an open bottom.

The construction of the side walls of the outer and inner caskets is clearly shown in Figs. 2 and 55

3, said walls being of tapered construction from the upper to the lower edges thereof for a purpose which will presently become apparent. While the end walls are not illustrated in detail, they are also of coacting tapered or outwardly beveled construction.

Disposed within the outer casket or shell 10 is an inner interment casket generally indicated at 13, and which may be of relatively cheap construction. The side walls 14 and 14a of the inner casket are beveled or inclined upwardly and telescoped within the walls 12a 12a of the outer casket, forming a relatively snug or tight fit. By this means the two caskets form a practically single unit and there is no tendency towards displacement of the inner casket with respect to the outer casket during handling. At the same time, it will be noted that the inner casket is free to move downwardly from the outer casket when the release mechanism, to be described, is operated.

The inner casket has a closed bottom 15 and a hinged lid or cover 16.

In order to fully conceal the inner casket or interment box from exterior view when the lid of the outer casket is open, a lining 17 is provided and has its one edge detachably connected to the lid 11 of the outer casket at 17a and its other edge connected to the lid or cover 11a as at 17b. 20 When the lid 16 of the inner box or casket is open, the lining 17 fully conceals the lid 16 as well as the entire inner box from exterior view, note particularly Fig. 2. To provide a symmetrical appearance when the outer and inner covers 25 are open, the outer cover is formed with a recess 17c in which the free edge of the inner lid engages.

The mechanism for releasing the interment box or inner casket is best shown in Figs. 3 and 4. The outer casket is provided with a pair of levers or latches 18, 18a each of which is pivotally connected to the outer casket as at 19. The inner casket is provided with stop members or lugs 20 and 20a which also serve as handles, and the pivoted latches 18, 18a engage beneath these lugs or handles 20, 20a when the outer and inner caskets are in telescoped engagement. The latches 18, 18a are held in latched position by means of a latch member 21 in the form of a screw bolt which is threaded through the end wall of the outer casket into engagement with the contiguous ends of said latch members.

To release the inner casket during interment, it is only necessary to retract the members 21 at each end of the casket, whereupon the inner

casket is permitted to rest on the lowering belt 22, note Fig. 3, said belt forming part of the usual casket lowering apparatus indicated at 23.

A casket of the type herein disclosed has a number of advantages over prior known caskets of this general type. Due to the relatively snug or close fit between the outer and inner caskets, the entire assembly may be used as a single unit. For example, the inner casket can be made of corrosion-resistant material and serve as a detachable lining for the outer casket in cases where expense is no consideration, any number of different types of liners being available. In the event the inner casket is to be used as an interment box, its snug fit ensures against displacement during use while at the same time it may be freely released from the outer casket. The operating mechanism is unusually simple and may be easily manipulated.

In the event cremation is desired, such procedure can be adopted conveniently and at a minimum of expense and still carry out the customary dignified funeral service.

It will be understood that certain limited changes in construction and design may be adopted without departing from the spirit and scope of the invention as defined by the appended claims.

What is claimed is:

1. A burial casket comprising outer and inner shells, each shell being provided with a lid capable of being raised to afford access to the interior of the shell, the outer shell having an open bottom to receive the inner shell, the inner side walls of the outer casket being inclined outwardly from their upper to their lower edges and the coacting surfaces of the side walls of the inner shell being inclined inwardly from the lower towards their upper edges to provide a snug interfit between the shells in a manner such as to simulate a substantially one-piece casket, the lid of one shell cooperating with the lid of the other shell to form a larger lid when the lids are in open position, and fastening means securing said shells in nested relation but permitting the shells to be separated, the coacting inclined surfaces of said shells permitting

release of the inner shell from the outer shell downwardly through the open bottom of the latter.

2. A burial casket comprising a dual receptacle intended to be used either as a unit for burying the dead or for use during a burial ceremony, said unit being separable into two parts; one a complete closed receptacle, and a second an exterior open-bottomed casing for said receptacle,

10 each of said parts having a lid, said parts when together being constructed to snugly interfit and present a unitary appearance with said lids cooperating to form a larger lid, the side walls being substantially solid and having their contiguous portions oppositely inclined to facilitate nesting one within the other, the inner shell being releasable from the outer shell through the open bottom of the latter.

3. A burial casket comprising an outer casket 20 adapted for re-use and having an open bottom, an inner casket or interment box in releasable telescoping engagement with said outer casket, the inner side walls of the outer casket being inclined outwardly from their upper to their lower edges and the coacting surfaces of the side walls of the inner casket being inclined inwardly from their lower towards their upper edges to provide a close-fitting engagement between the inner and outer caskets and at the same time permitting the inner casket to be released from the outer casket through the open bottom of the latter.

4. A burial casket comprising an outer casket 30 proper adapted for re-use and having an open bottom, an inner casket or interment box telescoped into said outer casket, said inner casket being provided with handle members, latch members pivotally connected to said outer casket for engagement with said handle members to hold the inner casket in engagement with the outer casket, and a threaded latch bolt projected through said outer casket for releasable engagement with said latch members, said latch engagement with said latch members, said latch bolt when released permitting the latch members to swing clear of the handle members.

RUDOLPH B. BERANEK.
